UNITED STATES PATENT OFFICE.

HIRAM T. BUSH, OF DETROIT, MICHIGAN.

DESIGN FOR A HINGE.

SPECIFICATION forming part of Design No. 31,488, dated September 5, 1899.

Application filed December 21, 1897. Serial No. 662,943. Term of patent 7 years.

To all whom it may concern:

Be it known that I, HIRAM T. BUSH, a citizen of the United States, residing at Detroit, county of Wayne, State of Michigan, have invented and produced a new and original Design for a Hinge; and I declare the following to be a full, clear, and exact description of the same, such as will enable others skilled in the art to which it pertains to make and use the same, reference being had to the accompanying drawings, which form a part of this specification.

Figure 1 is a plan view of the hinge. Fig. 2 is a side elevation.
15 In the drawings, A indicates the stem leading from the center of the crowning side of a round plate a. The plate a is flat on one side and crowning or rounded on the other. The stem A is round in cross-section and rises 20 and curves from the round plate a to its terminal, at which terminal there is a nearly globular head a'. The curvature of the stem A is such that the center of the head a' is about as far removed to one side of the vertical line that passes through the center of the plate a as it is in distance above the plane 25 which passes through the flat side of the plate a. Below the flat side of the plate a is a round bolt-shaped projection screw-threaded 30 on its free end.

At one side of the head a' is a globular head a, from which there extends downward the neck c', round in cross-section and curving

slightly until it has reached nearly to the lower plane of the plate a, where it curves 35 abruptly forward, with an arm that extends parallel (in the drawings) to the plane of the lower face of the plate a. The extreme length, however, of the arm c' is less than the vertical distance from the center of the head c 40 to the plane of the lower face of the plate a. At the other side of the head a' is the head d, from which a neck, round in cross-section, extends downward for a very short distance and bends abruptly forward to the hinge- 45 leaf d'.

The characteristic features of the design are comprised in the three nearly globular heads a' c d, of which the middle one, a, terminates the stem A, which rises from a round 50 plate a, and the two side globular heads which terminate stems by which they are connected to the leaves of the hinge.

The parts included and covered by this design are those which are usually visible when 55 the hinge is in use.

What I claim is—

The design for a hinge, substantially as shown and described.

In testimony whereof I sign this specification in the presence of two witnesses.

HIRAM T. BUSH.
